No. 798,805.

PATENTED SEPT. 5, 1905.

H. A. KURLFINKE.
APPARATUS FOR COMPRESSING HAMS.
APPLICATION FILED AUG. 3, 1904

UNITED STATES PATENT OFFICE.

HENRY A. KURLFINKE, OF SAN FRANCISCO, CALIFORNIA.

APPARATUS FOR COMPRESSING HAMS.

No. 798,805.

Specification of Letters Patent.

Patented Sept. 5, 1905.

Application filed August 3, 1904. Serial No. 219,296.

To all whom it may concern:

Be it known that I, HENRY A. KURLFINKE, a citizen of the United States, residing at San Francisco, in the county of San Francisco and 5 State of California, have invented certain new and useful Improvements in Apparatus for Compressing Hams, of which the following is a specification.

My invention relates to an apparatus for 10 pressing hams or meat into shape before cooking the same, the object of my invention being to provide an apparatus of this character which shall be cheap and simple in construction and rapidly and easily operated.

15 My invention also resides in the novel construction, combination, and arrangement of parts for the above ends hereinafter fully specified, and particularly pointed out in the claims.

20 In the accompanying drawings, Figure 1 is a perspective view of my apparatus. Fig. 2 is a perspective view of one of the jackets detached. Fig. 3 is a perspective view of the compressor detached. Figs. 4 and 5 are perspective views of the traveling nuts for holding the ends of the compressor. Fig. 6 is a detail perspective view of a portion of a jacket. Fig. 7 is a detail sectional view of the same. Fig. 8 is an enlarged broken side 25 view of one of the end stops.

Referring to the drawings, upon any suitable table or frame 1 are secured the heads 2 of the apparatus, in which is journaled a screw 3, having right and left handed screw portions 35 4 and 5 and operated by means of a hand-wheel 6. Upon said portions 4 and 5 travel the nuts 7 8, which are prevented rotating by means of a guide-bar 9, secured between the tops of said heads 2. By turning the hand-wheel 40 40 these nuts are caused to travel to or from each other. Upon transverse pins 10 11, secured, respectively, to said nuts, are loosely secured the ends of the compressor 12. This compressor is formed of a split strip of metal, 45 the unsplit portion of which passes between the split portions, as shown, and is adapted to surround a jacket 13, which is made of flexible sheet metal, perforated, as shown at 14, and in which the ham or other meat to be 50 compressed is placed. The meat having been placed within the jacket and the jacket having been inserted in place in the loops of the compressor, the hand-wheel is turned to cause the nuts to travel from each other, thereby reducing the diameters of said loops and compressing the jacket with great power. The

overlapping end 15 of the jacket travels over the under end as the compression takes place and in so doing hooks 16, formed by bending down portions of the upper end of the sheet-metal jacket adjacent to the edges thereof, pass over slots 17, cut near the edges of the jacket at its under end. These slots have their rear edges beveled, as shown at 18, the better to hold the hooks. Since these hooks pass over these slots 60 in succession as the compression takes place, it results that when the ham has been sufficiently compressed the hooks permanently remain in the farthest slots into which they have entered and automatically lock the jacket in position 65 around the ham. End stops 19 are now inserted in the ends of the jacket, consisting of wooden disks having sockets 20, in which slide latches 21, pressed out by springs 22, having finger-pieces 23 and stops 24. The ends of 70 these latches enter the perforations 14, but are prevented protruding therethrough by the stops 24. The ham is then boiled. After boiling the end stops are removed, the hand-wheel is reversed, the nuts are brought 75 together, loosening the compressor, and the jacket is removed from between the compressor, retaining the ham therein compressed ready for boiling. When the ham has been boiled, it contracts slightly on cooling, so that 80 the hooks can be withdrawn from the slots and the jacket removed from the ham.

25 represents a counter secured upon the guide-bar 9, having a pin 26 extending therefrom actuated by an upstanding arm 27, 90 mounted upon one of the nuts as it passes in one direction only of said nut, said arm yielding and passing under said pin when the nut moves in the other direction. This furnishes an automatic count of the number of hams 95 compressed.

The double screw being a great multiplier of power, and this again being further multiplied by the hand-wheel, very great pressure can be applied to the ham without much exertion on the part of the operator. 100

The jacket and end stops shown herein form no part of my present invention, which is confined to the press.

I claim—

1. In an apparatus of the character described, the combination of a right and left handed screw, nuts traveling thereon, a compressor comprising bands crossing each other, and having their ends secured to said nuts, 110 and means for turning said screw, substantially as described.

2. In an apparatus of the character described, the combination of a compressor comprising bands crossing each other, supports for the ends of said bands, and means for separating said supports, substantially as described.
3. In an apparatus of the character described, the combination of a compressor comprising bands crossing each other, supports for the ends of said bands, and a power-multiplying instrument for separating said supports, substantially as described.
4. In an apparatus of the character de-

scribed, the combination of a compressor comprising bands crossing each other, the bands from one side passing between the bands of the other side of the loop, supports for the ends of said bands, and means for separating said supports, substantially as described.

In witness whereof I have hereunto set my hand in the presence of two subscribing witnesses.

H. A. KURLFINKE.
